UNITED STATES PATENT OFFICE.

JEAN K. VANATTA, OF CHICAGO, ILLINOIS, ASSIGNOR TO MUDGE & COMPANY, OF CHICAGO, ILLINOIS, A CORPORATION OF ILLINOIS.

DESIGN FOR AN ENGINE-BASE FOR MOTOR-CARS.

53,541.

Specification for Design.

Patented July 8, 1919.

Application filed February 2, 1918. Serial No. 215,213. Term of patent 14 years.

To all whom it may concern:

Be it known that I, JEAN K. VANATTA, a citizen of the United States, and a resident of the city of Chicago, county of Cook, and State of Illinois, have invented a new, original, and ornamental Design for an Engine-Base for Motor-Cars, of which the following is a specification, reference being had to the accompanying drawing, forming part thereof.

The drawing is a perspective view of my novel design.

I claim:

The ornamental design for an engine base for motor cars, as shown.

JEAN K. VANATTA.
